PRINTING MECHANISM AND IMPRESSION
CYLINDER THEREFOR

Frank G. Breyer, Wilton, Conn., assignor to J. M. Huber, Inc., New York, N. Y., a corporation of New Jersey

Application July 11, 1940, Serial No. 344,886

7 Claims. (Cl. 101—407)

This invention relates to printing apparatus intended particularly for use in the practice of the recently-developed "cold set" printing process described in a co-pending application of Walter Huber, Serial No. 288,113, filed August 3, 1939.

In the practice of said process, the inking rollers and printing form of each printing mechanism must be heated to elevated temperatures substantially above the melting range of the normally solid thermo-fluid ink to be printed. For high speed newspaper printing, such as at web speeds of 600 to 1500 linear feet per minute, I have found it advantageous to use printing temperatures well above 210° F., as set forth in my co-pending application, Serial No. 344,885, filed of even date herewith. When using such elevated printing temperatures, however, heat exchange between the hot printing form of each printing mechanism and the surface of the adjacent impression cylinder tends to raise the temperature of the latter to such a point that it becomes somewhat plastic. The usual printing press impression cylinder is formed with layers of elastic cushioning material supporting a top or surface sheet of rubber or other thermo-plastic material. Excessive heating of this thermo-plastic material, together with the constant impact and deforming pressure of hot printing surfaces thereagainst during printing operations, has been found to result in such indentation or marring of the impression cylinder surface that printing results are seriously impaired. This difficulty has been particularly evident when printing with high speed news-paper presses in which the impression cylinders are constantly held close to the heated printing cylinders and consequently tend to become quite hot.

An object of my present invention is to provide new and improved printing apparatus and new impression cylinders therefor which can be used without difficulty in printing according to said "cold set" process. Another object of this invention is to provide a new impression cylinder construction which possesses the required elasticity or cushioning action and at the same time resists heat and remains smooth and uniform in surface qualities over long periods of use at elevated printing temperatures.

I have discovered that the difficulties encountered with impression cylinders of known construction can be avoided and that the "cold set" printing process can be carried out with improved results by providing each printing mechanism with an impression cylinder having a special cov-

ering of very finely woven, heat-resistant fabric. In preferred embodiments of my invention this covering consists of a finely-woven fabric such as balloon cloth, which, if desired, may be provided with a thin coating containing aluminum powder. The balloon cloth covering may be applied to the cylinder as part of a laminated top sheet consisting of layers of balloon cloth enclosing an intermediate thin layer of rubber or other suitable cushioning material, which top sheet is drawn tightly over an elastic supporting structure comprising laminations of coarser fabrics and cushioning materials of the kinds usually employed as supporting blankets in the construction of printing press impression cylinders.

The finely woven cloth surface of the new impression cylinders resists indentation or deformation during long periods of service at printing temperatures as high as 230° F. and higher. This result is achieved even though the cloth surface be positioned next to a thin layer of rubber or rubber-like material, as the latter is enclosed between and protected by balloon cloth layers. The tightness and finely woven quality of the balloon cloth strands prevent them from being spread by the pressure of small half-tone dots or other small printing characters carried by the hot printing form, and the balloon cloth or the like presents a smooth impression surface free from irregularities or level variation that would adversely affect printing quality. Notwithstanding these characteristics, the covering fabric yields under the pressure of the printing surfaces and thus prevents the latter from damaging the paper web during printing operations. In addition, the fabric is resistant to water and oil, even at elevated temperatures, so that the new construction can be used to advantage whenever a spray of water-oil emulsion or other suitable liquid treatment is used for the surface of the impression cylinder during the printing operations, according to the disclosure of my aforementioned co-pending application.

An illustrative embodiment of apparatus embodying my invention is shown in the accompanying drawing, forming a part hereof, in which:

Figure 1 is a schematic view, in vertical cross section, showing part of a newspaper printing mechanism embodying the invention;

Figure 2 is an enlarged perspective view of the impression cylinder with portions of the cushioning and covering materials broken away to reveal the composite construction; and

Figure 3 is an enlarged fragmentary cross section through the periphery of the impression cylinder.

Referring to the drawing for details of the illustrated embodiment, Figure 1 shows one printing mechanism of a high speed rotary letter-press such as may be used for high speed newspaper printing according to the "cold set" process. A printing cylinder P and an impression cylinder S are arranged side by side in closely spaced relation. The printing cylinder carries a printing form F, usually consisting of stereotype printing plates. The printing form rotates in contact with inking rollers I, which form parts of an inking mechanism (not shown) that feeds molten thermo-fluid ink from an ink furnisher and distributes it evenly onto the relieved printing surfaces of the rotating form. The printing cylinder P, as shown, is made hollow and is heated to elevated printing temperatures by circulation of hot water therethrough. The water heating system is not shown in the drawing because it forms no part of the present invention.

The web A to be printed passes through the bite between the printing cylinder P and the impression cylinder F and thence over a cooling roller C, which is held at a suitably low temperature by internal circulation of cold water. As the web travels between the two cylinders it is impressed with films of molten thermo-fluid ink carried on the printing surface of the form F. The hot molten ink films so printed adhere to the web and freeze to a solid condition by loss of heat into the web immediately upon leaving the printed surfaces. Their final solidification to a hard, mar-resistant condition is effected by the chilling action of the cooling roller C.

The impression cylinder S, as shown more fully in Figure 2 and Figure 3, comprises a rigid cylindrical core 10 which is surrounded by laminations 20 and 30 of elastic cushioning materials and covered tightly by a top sheet 40 having a surface fabric of balloon cloth or other similar thin, finely-woven fabric.

In the illustrated embodiment, as shown in Figure 3, the lowermost lamination 20 consists of coarsely woven fabrics 22 and 24 enclosing an intermediate layer 26 of rubber or rubber-like composition. The next lamination 30 consists of coarsely woven fabrics 32 and 34 enclosing a layer 36 of cork composition or the like. The top sheet 40 consists of two layers 42 and 44, each of balloon cloth, and a thin intermediate layer 46 of rubber or rubber-like composition. As an example only, the thicknesses of laminations 20, 30 and 40 may be about .062", .062" and .025", respectively. The stippling on the face of the top sheet 40 in Figures 2 and 3 is intended to indicate the presence on the outer balloon cloth layer 44 of a thin protective coating containing aluminum powder.

It will be understood that the blankets underlying the top sheet may be made of various types of cushioning materials and may be arranged in any number, order or thickness as long as the required elasticity or cushioning effect is obtained. The important feature is to utilize the surface characteristics and heat resistance of the

balloon cloth covering, which provides a smooth, uniform, yieldable impression surface and protects the impression cylinder against damage formerly caused by high temperature conditions in conjunction with the impact and pressure of hot printing surfaces thereagainst at high printing speeds. It will also be understood that other finely-woven cloths having similar qualities may be used in place of balloon cloth, and that various types of protective coatings may be used on the surface cloth. Indeed, the use of a surface coating may be dispensed with altogether without departing from the broader contribution of this invention.

It will therefore be apparent that the invention should be accorded a scope commensurate with its novel contributions to the art, as intended to be set forth in the appended claims, without restriction to non-essential details of the illustrated embodiment.

I claim.

1. A rotary printing mechanism for printing molten thermo-fluid ink comprising a printing cylinder, heating means therefor, and an impression cylinder adjacent thereto having a covering of smooth, finely-woven, heat-resistant fabric.

2. A rotary letter-press printing mechanism for printing molten thermo-fluid ink comprising a printing cylinder adapted to carry a printing form, heating means therefor, an impression cylinder adjacent thereto having a covering of smooth, finely-woven, heat-resistant fabric, and an elastic backing for said fabric yieldable under pressure from said form.

3. A rotary letter-press printing mechanism for printing molten thermo-fluid ink comprising a printing cylinder adapted to carry a printing form, heating means therefor, an impression cylinder adjacent thereto having a covering of smooth, finely-woven, heat-resistant fabric, and an elastic backing for said fabric comprising laminations of fabrics and cushioning materials.

4. A rotary letter-press printing mechanism for printing molten thermo-fluid ink comprising a printing cylinder adapted to carry a printing form, heating means therefor, and an impression cylinder adjacent thereto having a tight covering of balloon cloth supported by an elastic backing.

5. An impression cylinder for a printing press or the like comprising a rigid cylindrical core, elastic cushioning materials surrounding said core, and a covering of smooth, finely-woven, heat-resistant fabric.

6. An impression cylinder for a printing press or the like comprising a rigid cylindrical core, a plurality of laminations of fabrics and elastic cushioning materials surrounding said core, and a tight covering sheet over said laminations having inner and outer layers of balloon cloth and an intermediate thin layer of elastic cushioning material laminated thereto.

7. An impression cylinder for a printing press or the like having a surface of balloon cloth with a thin coating thereon containing aluminum powder.

FRANK G. BREYER.
